UNITED STATES PATENT OFFICE.

EARL M. WILSON, OF ST. PAUL, AND EARNEST S. SEAMAN, OF MINNEAPOLIS,
MINNESOTA.

RAILWAY-SWITCH POINT.

1,390,850.

Specification of Letters Patent. Patented Sept. 13, 1921.

Application filed May 16, 1921. Serial No. 469,854.

To all whom it may concern:

Be it known that we, EARL M. WILSON and EARNEST S. SEAMAN, citizens of the United States, residing, respectively, at St. Paul, in the county of Ramsey and State of Minnesota, and Minneapolis, in the county of Hennepin and State of Minnesota, have invented a new and useful Railway-Switch Point, of which the following is a specification.

Our invention relates to railway track construction and more particularly to the construction of diverging tracks such as main and side track or main and spur track at their point of divergence.

The object is to provide railway-switch points of substantial construction and so constructed that the part of the switch point getting the hardest wear may be readily detached and a new point substituted and the balance of the switch point with its pivot is retained for further use, thus eliminating a large and expensive waste of material common to many railways.

In the drawing:

Figure 1 is a top view of a portion of main line track showing also a portion of side track at its converging point with the former and including our improved switch point and a switch post.

Fig. 2 is an enlarged detail top view of one of our improved switch points in operative contact with a main track rail, the tread and web of the latter being shown dotted.

Fig. 3 is a side elevation of the switch point in Fig. 2 with the right hand portion of one reinforcing plate broken away.

Fig. 4 is a vertical elevation of our switch point as seen from the right of Fig. 2.

For descriptive purposes the straight rails in the drawing will be called the main track rails and the rails diverging therefrom called spur track rails.

Referring to the drawing by reference numerals, 5 are the ties 6 and 7 the right and left rails, respectively, of a main track and 8 and 9 the right and left rails, respectively, of a spur track diverging from said main track. 10 and 11 are right and left switch points having pivot lugs 12 on the underside at their large ends for pivotally engaging an aperture in a plate 13 or other equivalent construction may be used.

14 represents a switch operating post of usual construction mounted near the track and having the hand lever 15 which operates connecting rod 16 and the rod 17 attached as at 18 to the switch points to operate them.

The operation of the switch points illustrated in Fig. 1, dotted lines indicating their position when the main track is in use, the full lines indicate position of the points when it is desired to run a train from the main track on to the spur track or vice versa.

It is readily understood that when a train is to be switched from the main track on to the spur, there is a tremendous side pressure and consequent wear at the pointed end of the switch point rail 11 which can not be overcome. The present practice of throwing away the entire rail 11 when the point is worn is costly and extravagant and our invention eliminates this waste by the following construction.

As illustrated in Figs. 2 and 3, our device in general appearance is the same as a switch point of the present type of standard rail, the inner side of the rail tread, as 19, being a straight line to the point 20, and the outer side 21 parallel thereto only as far as to point A which touches inside line 22 of main line rail 7. The vertical face 23 of the switch point, between A and point 20 is held against main line rail 7 when a train is to be run in on spur track 8-9, the point on the other side being swung inward simultaneously by rod 17 allowing wheel flanges of train to follow rail 8 when the left hand flanges contact with the switch point as described and continue on to rail 9 of the spur track.

From a predetermined point as B and to the end 20 of the rail 11 we cut away the tread of said rail on a horizontal line 24 (see Fig. 3) and provide a number of notches 25 in the web 25* for receiving corresponding web tongues 26 of a detachable switch point 27, held in place by bolts 28 passing through apertures in said web and tongues and in two opposite plates 29. The bolt heads are countersunk in the plates (see Fig. 4) for clearance to allow point 20 to be brought up close against the adjacent rail, as 7 or 8 (Figs. 1 and 4).

Plates 29 are made as wide as possible to fill in between the tread and the base

flange of the rail and extend back far enough to hold the removable point firmly in the web 25 of the rail 11.

30 is a ledge at the top of web 25* near the extreme point 20 and tapering toward the large end of rail point 27 according to the angle of said point when it is in contact with rail 7, (see Fig. 2) said ledge or clearance passing under the tread of the main rail to allow full closing of the switch.

What we claim is:

1. A railway switch point consisting of a main section pivotally jointed at one end to the main track rail and having at the other end the tread of the rail cut away and the web of rail therebelow formed with gaps having vertical edges; a second joint section comprising mainly a rail tread portion with downward lugs fitting in the said

gaps, fish-plates extending one along each side of said sections and bolts having countersunk heads and extending horizontally through said fish-plates and the intermediate web and lugs, for securing the parts together; said second section being wedge-shaped toward its free end and removable upward when the bolts through its lugs are withdrawn.

2. The structure specified in claim 1, the gap nearest the free end of the main point section being open also toward the said end of the section, so as to expose the lug therein to the contact of a car-wheel entering the switch point.

In testimony whereof we affix our signatures.

EARL M. WILSON.
EARNEST S. SEAMAN.
